Primary Examiner — Stacia Cadmus(74) *Attorney, Agent, or Firm* — Wood Herron & Evans LLP(57) **CLAIM**

The ornamental design for a wheel, as shown and described.

DESCRIPTION

FIG. 1 is a front perspective view of a wheel according to the present invention.

FIG. 2 is a front view of the wheel shown in FIG. 1.

FIG. 3 is a side view of the wheel shown in FIG. 1.

FIG. 4 is a front perspective view of a second embodiment of the present invention.

FIG. 5 is a front view of the wheel shown in FIG. 4; and, FIG. 6 is a side view of the wheel shown in FIG. 4.

The broken line showing of the rim of the wheel, the valve stem hole, the bolt holes and the center hole is included for the purpose of illustrating environmental subject matter and forms no part of the claimed design.
